UNITED STATES PATENT OFFICE.

LEOPOLD LACINY, OF ST. LOUIS, MISSOURI, ASSIGNOR TO LOUIS D. LOEVY, OF ST. LOUIS, MISSOURI.

HYDROCARBON-BURNER.

1,183,989.

Specification of Letters Patent.

Patented May 23, 1916.

Application filed March 6, 1916. Serial No. 82,502.

To all whom it may concern:

Be it known that I, LEOPOLD LACINY, a citizen of the United States, residing at the city of St. Louis, State of Missouri, have 5 invented a certain new and useful Improvement in Hydrocarbon-Burners, of which the following is a specification, reference being had to the accompanying drawing, forming a part thereof.

10 This invention relates to a certain new and useful improvement in hydrocarbon burners, the principal object of my present invention being to provide a burner of the kind stated of comparatively simple and 15 inexpensive form and construction and efficient in operation, the hydrocarbon fuel supplied to the burner being thoroughly vaporized in the burner to a relatively high temperature and, on discharging from the 20 burner, burning with approximately perfect combustion in a substantially uniform, steady, intensely hot, blue flame.

With the above and other objects in view, my present invention resides in certain novel 25 features of form, construction, arrangement, and combination of parts, all as will herein-after be described and afterward pointed out in the claims.

In the accompanying drawing, in which 30 I show my new burner separate from any heating or cooking apparatus, although it is to be understood that my burner may in use and practice be employed in connection with a stove, furnace, boiler, or other heating 35 or cooking apparatus or the like,—Figure 1 is a side elevational view of a burner embodying my invention, the burner being shown in operative connection with a hydrocarbon supply or feed tank; Fig. 2 is an 40 enlarged side elevational view, partly in section; and Fig. 3 is an enlarged top plan view of the burner.

Referring to the said drawing, in which like reference characters refer to the same 45 parts throughout the several views, 1 indicates a preferably elongated rectangular base-pan having an upstanding side-wall or flange 2 extending therearound and provided centrally with a longitudinal channel 50 or depression 3. Preferably adjacent the ends of channel 3, pan 1 is provided with suitable standards 4—4 adapted, as shown, to support the burner proper, a horizontally disposed pipe or tubular section 5 forming 55 the intermediate chamber, as I have termed

it, of the burner extending longitudinally of pan 1 directly above and preferably centrally of channel 3.

Leading from tubular section or intermediate chamber 5 of the burner is a discharge-nozzle 6 having an outlet opening or aperture 7 presented upwardly and of any suitable relatively reduced diameter. Suitably mounted on nozzle 6 and surrounding the mouth of outlet 7 is an oil-cup 8.

Communicating at one end with intermediate chamber 5 is an upstanding or vertically disposed pipe or tubular section 9 provided with what might be called a goose-neck portion 10, fixed to, and closing the end of, which is a preferably circular plate or flame-spreader 11. This plate 11, which is of suitable size and diameter, is, as illustrated, disposed horizontally directly above, but spaced suitably from, nozzle 6. Pipe 9 provides what I will, for purposes of description, call the reservoir chamber of the burner. Communicating at one end with the other end of tubular section or intermediate chamber 5 is an elongated burner pipe comprising a short vertically disposed portion 12, a coiled or looped portion 13, and an extension 14 leading to a hydro-carbon-supply-tank or the like 15. The coiled or looped portion 13, the greater part of which is approximately horizontally disposed directly beneath plate or flame-spreader 11 and above nozzle 6 and its outlet-opening 7, provides what I will, also for purposes of description, call the vaporizing chamber of the burner.

As I prefer in practice to force the hydrocarbon, and I may here say that I preferably employ with my new burner coal-oil as the hydrocarbon fuel, into the burner under a compressed air or other fluid pressure of approximately thirty pounds, tank 15 has suitable valve-controlled communication with a compressed air or other fluid pressure tank 16, a suitable needle-valve or the like 17 interposed in burner-extension 14 being adapted to regulate or control the flow of the hydrocarbon fuel under pressure from tank 15 into the burner.

In use or operation, to first heat the burner pipes or chambers to vaporizing temperature, a small quantity of coal-oil or the like is placed in channel 3 of pan 1; at the same time, valve 17 is opened and a quantity of coal-oil under pressure sufficient to approxi-

mately fill the burner-chambers is also permitted to flow thereinto from tank 15, this fuel, first as liquid and afterward as vapor, finding escape from the burner through 5 nozzle-opening 7. Valve 17 being now closed, and on the coal-oil or the like in pan 1 and the coal-oil escaping as liquid into cup 8 being ignited, the burner-chambers, and particularly chambers 9 and 13, 10 are heated and raised to vaporizing temperature, the coal-oil in the burner chambers being thereby vaporized and then escaping through, and burning at, nozzle-opening 7 as vapor. As soon as the flame of the vapor 15 burning at outlet 7 begins to flicker, indicating or signaling that the vapor supply in the burner is exhausting, valve 17 is again opened and, in the continued operation of the burner, permitted to remain open, 20 when coal-oil under pressure flows from tank 15 into the burner-extension 14. On the oil flowing into vaporizing-chamber 13, the same is vaporized and now as vapor enters intermediate chamber 5, from which some of 25 the entering vapor under pressure escapes through, and burns at, nozzle-outlet 7 and some flows into chamber 9. The vapor entering chamber 9, being there further subjected to the heat of the flame of the burning vapor, 30 acts or performs the function of a buffer, so to speak, on the principle somewhat of a water-dome, for the vapor entering chamber 5 and tends to prevent fluctuation of the flame of the vapor escaping at outlet 7, the 35 escaping vapor burning, as I have found from experience, in a steady, intensely hot, approximately blue flame practically without odor or dirt. On valve 17 being again closed, the burner will gradually burn out. 40 I am aware that minor changes in the form, construction, arrangement, and combination of the several parts of my burner may be made and substituted for those herein shown and described without departing

from the nature and principle of my invention.

Having thus described my invention, what I claim and desire to secure by Letters Patent is:

1. A hydrocarbon burner comprising an 50 approximately horizontally disposed chamber provided with an upwardly presented vapor-discharge outlet, an approximately horizontally disposed vaporizing-coil 55 located in proximity to, and above, said outlet and having communication with said chamber, said coil being adapted for communication with a liquid fuel-supply, an extension on said chamber projecting upwardly therefrom and having an end in proximity 60 to said outlet, and a flame-spreading member disposed above said outlet and over the greater part of said coil, said member being supported by and at said end of said extension. 65

2. A hydrocarbon burner comprising an approximately horizontally disposed tubular chamber provided with an upwardly disposed vapor-discharge outlet, an approximately horizontally disposed vaporizing-coil 70 located in proximity to, and above, said outlet, said coil being adapted for communication with a liquid-fuel supply, a second tubular chamber having angular relation to said first chamber and also located in proximity to said outlet, whereby both said second chamber and said coil receive heat from vapor discharging and burning at said outlet, said first chamber being located intermediate said coil and second chamber and having 75 communication with both said coil and second chamber, and a flame-spreading plate supported approximately horizontally by said second chamber above said outlet and over the greater part of said coil. 80 85

In testimony whereof, I have signed my name to this specification.

LEOPOLD LACINY.
